CLAIM

The ornamental design for a fishing rod grip accessory as shown and described.

DESCRIPTION

FIG. 1 is a first side view of the design;

FIG. 2 is second side view of the design;

FIG. 3 is a third side view of the design;

FIG. 4 is first perspective view of the design;

FIG. 5 is a second perspective view of the design;

FIG. 6 is a top end-on view of the design; and,

FIG. 7 is a bottom end-on view of the design.

The broken lines depict portions of the fishing rod grip accessory that form no part of the claimed design.
